(57) **CLAIM**

The ornamental design for a storage case, as shown and described.

DESCRIPTION

FIG. 1 is a front perspective view of a storage case shown in the closed position;

FIG. 2 is a top view thereof;

FIG. 3 is a front view thereof;

FIG. 4 is a bottom view thereof, with the latch shown in an unlatched position;

FIG. 5 is a rear view thereof; and,

FIG. 6 is a right side view thereof, the left side view being a mirror image of the left.
